ABRASIVE ROLL

Charles L. Shaw, Dayton, Ohio, assignor to Lectro Manufacturing, Inc., Middletown, Ohio, a corporation of Ohio

Filed May 16, 1958, Ser. No. 735,860

3 Claims. (Cl. 51—190)

This invention relates to improvements in abrasive rolls. More particularly, this invention concerns forming a roll of abrasive material having a central opening which is formed in a particular manner to facilitate a firm, tenacious seating of the roll upon a drive mandrel. Abrasive rolls presently available for use on drive mandrels are difficult to mount and very often slip thus preventing efficient use through application of high working pressure with attendant high torques. Further, the past rolls are highly subject to tear-out under high torque conditions.

This invention is concerned with providing an internal shape to abrasive rolls which will result in better engagement with the drive mandrel to prevent slippage or tear-out and to permit greater efficiency and effectiveness in use of the unit by simplifying mounting and eliminating separate handling procedures in tightening the roll upon the drive mandrel or arbor.

An object of this invention is to form an abrasive roll with a central opening peculiarly suited to quickly and firmly seating the roll upon a shouldered drive mandrel.

Another object of this invention is to provide a pattern shape for an abrasive sheet which, upon rolling, will produce a roll having a central opening particularly suited to seat on a drive mandrel.

A further object of this invention is to provide an abrasive roll having a central opening designed to positively engage a drive mandrel without slippage or tear-out.

A still further object of this invention is to provide an abrasive roll having a central opening shaped to firmly grab a mandrel to permit high torque usage of the roll and consequent rapid abrasive action.

These and other objects and advantages of this invention will be apparent from the following description and claims.

In the accompanying drawings which illustrate by way of example various embodiments of this invention:

Fig. 1 represents a pattern for abrasive sheets to be formed into abrasive rolls.

Fig. 2 is a longitudinal cross sectional view of an abrasive roll;

Fig. 3 is a plan view of an abrasive sheet prepared for rolling;

Fig. 4 is a perspective cross sectional view of a particular form of abrasive roll;

Fig. 5 is a side elevation view, partly in section, showing an abrasive roll being mounted on a drive mandrel to form an abrading unit.

Fig. 6 is a plan view of a modified abrasive sheet prepared for rolling;

Fig. 7 is a longitudinal cross sectional view of an abrasive roll formed from the sheet shown in Fig. 6.

The sheet 1, as shown in Fig. 1, has a base edge 2 and a side 4. The portion of the sheet 1 comprising the corner formed by side 4 and the base edge 2 is removed by severing the sheet along a line 3. This line of severance is shown as a straight diagonal line forming an obtuse angle with the remainder of the base edge. The

2

manner of severance shown is the preferred form; however, the line 3 may also be sinuous, arcuate, serrated or of other configurations. The sheet 1 is coated with an abrasive material on one surface.

5 The abrasive roll 6 shown in Fig. 2 is the result of winding a sheet such as is shown in Fig. 1 into several convolutions. By commencing the winding operation with the base edge 2, the removed portion of the sheet, as defined by the line 3, results in a frusto-conical or step-tapered opening 7 coaxial with the abrasive roll and adjacent one end. The first roll or turn of the base edge is made of sufficient diameter to provide a cylindrical opening 8 extending from the conical opening 7 through the cylinder. While the opening 7 is of a general conical shape, it is to be noted that it is actually tapered in steps corresponding to the spiral shoulders 3a resulting when edge 3 is formed into a spiral by the winding operation.

The abrasive sheet 10 shown in Fig. 3 illustrates the 20 embodiment of the current invention in a sheet designed to form a tapered abrasive roll. The sheet 10 has a base edge 12 and a diagonal corner edge 13 and side 14 corresponding to edges 2, 3 and 4 respectively of the sheet shown in Fig. 1. In addition, the sheet 10 has one

25 major diagonal side 15 opposed to base edge 12 resulting in one short side 16 adjacent base edge 12. Winding of the sheet 10 commencing with base edge 12 results in the formation of a hollow core from that longitudinal portion of sheet 10 corresponding to the length of side

30 16 and subsequent continued winding results in the step-tapered configuration represented in roll 19 shown in Fig. 4. The edge 15 becomes an external helical shoulder on the step-tapered roll 19. The edge 13 forms a tapered seat in roll 19 as is disclosed in Fig. 4. In the embodiment disclosed in Figs. 3 and 4 the edge 13 is disposed to form a steep pitched helical shoulder 13a when the sheet is wound into a roll. This shoulder may extend over less than one convolution of the completed roll.

Fig. 5 illustrates an abrading tool unit comprising a 40 tapered roll 19 and a drive mandrel 20 being assembled. The shadow lines 45 indicate the final seated position of the roll 19 on the mandrel 20. The drive mandrel 20 is provided with a helically threaded, tapered seating shoulder 21 joining a major diameter shank portion 45 22 with the mounting arbor extension 23. As the roll 19 is mounted upon the arbor 20, the extension 23 is received by cylindrical opening 8a permitting the roll to slide over the mandrel or arbor 20 until shoulder 21 engages shoulders 23a of the conical opening 27. It can readily be seen that the mating of such a tapered shoulder with a tapered opening provides a large area of engagement between the driving and driven parts and thus insures a firm and tenacious engagement.

The embodiment of the invention shown in Fig. 6 and 55 Fig. 7 contemplates the making and utilization of a sheet which will form a roll having the tapered seating portion disposed within the roll rather than adjacent one end. In this modification sheet 30 has a base edge 32, a first line or edge 35 parallel to base edge 32 and commencing 60 at and proceeding inwardly from one of the sides as side 36, adjacent edge 32. A second line of cut has been made to form diagonal edge 33 which joins base edge 32 and the edge resulting from the line of cut 35. The line of severance of edge 33 is disposed at an obtuse angle relative to the remaining base edge 32. It can readily be seen that cutting along lines 33 and 35 will sever or remove a portion of one corner of the sheet 30. Subsequent to preparation of sheet 30, it is wound into a roll, commencing with base edge 32, to form an abrasive roll of the general configuration of the roll 38 shown in Fig. 7. It is to be noted that the configuration of sheet 30 results in a disposition of the conical seat-

ing portion 37 internally of the roll rather than adjacent one end. It is to be understood that this configuration results in a roll which will seat further back on a mandrel and provides the area of effective engagement of the roll with the mandrel nearer the geometrical center of the roll and consequently places the point of force or torque application to the roll nearer to the center of forces resulting from the abrasive action of the roll.

The criterion for determining the angle of side 3, 13 or 33 with respect to the adjacent sides is that the included angle A (see Fig. 5) defined by the resulting tapered opening should be less than the included angle B defined by the shoulder 21 of the mandrel. Thus, for use on many mandrels currently utilized in industry, applicant has found that the preferred form of his invention is wherein the edge 3, 13 or 33 makes a large obtuse angle, approaching 180° with the remaining edge 2, 12 or 32. The resulting helical shoulder, as 13a, is then of a steep pitch and may extend over less than one convolution of the resulting roll as illustrated in Fig. 4. This configuration has the added advantage that the shoulder 13a is disposed at a greater angle to the threads of shoulder 21 to facilitate firm engagement and easy assembly.

In each of the above structures, it is to be noted that a considerable portion of the sheet is of full width along a substantial portion of sides 4, 14 and 36. This configuration results in a rolled structure having several convolutions of material, as at 39, 40 and 41, backing up the entire length of the area of the conical openings 7, 27 and 37. These convolutions serve to back up the stepped convolutions forming the step-tapered area to prevent stretching of the material and expansion of the opening, thus maintaining a firm grip between the drive mandrel shoulder and the conical shoulder of the roll.

It can readily be seen that the above disclosed structure results in a roll having a seating shoulder which permits quick but tenacious engagement between the roll and the driving mandrel or arbor. The greater area of engagement and the firmer grab had by the mandrel upon the drive roll prevents slippage of the roll upon the mandrel. Also, the frequency of tear-out has been greatly reduced, due to the more and increased area of jointure between the parts.

The size and taper of the conical portion of the opening may, of course, be varied to suit individual work applications and the particular mandrels or arbors involved. Further, the general outline of the abrasive sheet may be varied in many shapes to effectuate final various outside contours of the resulting abrasive roll.

The rolls here concerned are formed with the abrasive coated side of the sheet material on the outer side of the roll.

It is also possible to approximate the step-tapered design resulting from the above structure in other ways as

by rolling an ordinary sheet of abrasive material and thence drilling or countersinking from one end to form a conical shoulder. Such a countersinking results in a truer conical configuration but does not provide the helical ridges or shoulders of the above described preferred internal structure.

While the invention has been described in connection with different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth and as fall within the scope of the invention or the limits of the appended claims.

Having thus described my invention, what I claim is:

1. An abrading unit comprising in combination, an abrasive roll and a drive mandrel in assembled relationship, said abrasive roll formed with a coaxial opening having a substantially frusto-conical portion and a cylindrical portion, said drive mandrel having a shank portion, a mounting arbor of lesser diameter than said shank portion and a tapered seating shoulder between said shank portion and said mounting arbor, wherein said seating shoulder engages said roll with said frusto-conical portion and said mounting arbor extends into said cylindrical portion.
2. An abrading unit comprising, in combination, an abrasive roll and a driving mandrel, said abrasive roll formed of wound sheet material having an abrasive coating thereon, said roll formed with a coaxial opening having a substantially frusto-conical portion and a cylindrical portion, said drive mandrel having a tapered seating shoulder, wherein the included angle defined by said opposite sides of said substantially conical portion is less than the included angle defined by said tapered seating shoulder, said roll mounted on said mandrel with said substantially frusto-conical portion engaging said seating shoulder.
3. An abrading unit as in claim 2 and wherein said substantially conical portion is step-tapered in a manner defined by a helically disposed edge of said wound sheet material and wherein said tapered seating shoulder is threaded.
